H. B. INGLIS.

WIND COMPENSATOR FOR AIRCRAFT GUNS.

APPLICATION FILED APR. 18, 1922.

Patented Oct. 24, 1922.

H. B. Inglis Inventor

Robert A. Young attorney

UNITED STATES PATENT OFFICE.

HENRY B. INGLIS, OF DAYTON, OHIO.

WIND COMPENSATOR FOR AIRCRAFT GUNS.

Application filed April 18, 1922. Serial No. 555,196.

To all whom it may concern:

Be it known that I, HENRY B. INGLIS, a citizen of the United States, residing at Dayton, in the county of Montgomery and State of Ohio, have invented certain new and useful Improvements in Wind Compensators for Aircraft Guns, of which the following is a specification.

This invention relates to wind compensating means for aircraft gun turrets, the object in view being to automatically counteract or compensate for the pressure of the wind which tends to turn an aircraft gun mounted on a revoluble turret, when the aircraft is in flight.

A further object of the invention is to accomplish the desired result by means of a mechanical linkage between the revoluble turret and the base on which it is revolubly mounted. The wind pressure against the gun varies for different angular positions of the gun with respect to the line of flight of the aircraft. By means of this invention an equal but opposing turning movement upon the gun turret is automatically obtained thus causing an equilibration of forces on the gun and compensating for windage in any position of the gun. The gunner is thus relieved by the very considerable force of the wind against the gun in shifting the turret or in holding the gun laterally of the fuselage when the turret is not locked in position.

The invention consists in the novel construction, combination and arrangement herein fully described, illustrated and claimed.

In the accompanying drawings:

Figure 1 is a broken plan view of a revolving turret flexible gun mount, showing the wind compensating means applied thereto; and

Figure 2 is a fragmentary vertical sectional view of the same.

The flexible gun mount comprises a fixed annular base 1 upon which is mounted a revoluble turret 2. Connected to the turret by trunnions 3 is a scarf ring 4 on which the gun 5 is mounted by means of a pivot 6 which enables the gun to be swung laterally. Elevation of the gun is obtained by means of the trunnions 3, which permit the ring 4 to be raised and lowered.

When the aircraft is flying in the direction indicated by the arrow *a* there is a strong wind pressure against the gun in the direc-

tion indicated by the arrows *b* said pressure varying as the angle of the gun in relation to the path of flight *a* and wind pressure *b* varies.

To counterbalance or compensate for such wind pressure against the gun tending to turn the turret, I have devised the following automatically acting mechanism. The base 1 is provided with an internal rack or toothed face 7 for cooperation with a train of gears. One of the gear wheels 8 mesh with the rack face 7 and also carries a pinion 9 which meshes with a gear wheel 10. Gear wheel 10 carries a projecting pin 11 which works in an arcuate cam slot 12 in a cam 13. The cam 13 is in the form of a cross head on one end of a plunger or piston rod 14. At the other end of plunger 14 there is a head 15 which is movable back and forth in a cylinder or housing 16 containing an expansion element 17 such as a spring.

The cylinder 16 is fastened to the ring like body part of the turret 2 and the gear wheels above described are also mounted in bearings carried by the turret, the gear face 7 being immovable.

In the operation of the mechanism, wind pressure against the gun 5 tends to turn or partially revolve the turret. As the turret starts to turn, gear wheel 8 is caused to turn and impart movement to the train of gears. This causes pin 11 to be shifted along the cam slot 12. This causes movement of the plunger 14 resulting in more or less compression of spring 17. The cam 13 is so designed in relation to the sweep of the pin 11 and the strength of the spring 17 that the turning moment offered by the latter will vary proportionately to the turning moment against the gun as the angle of the turret is changed.

What I claim is:

1. In a flexible gun mount for aircraft, a fixed base having an annular rack face, a revoluble gun-supporting turret mounted on said base, and wind pressure compensating means embodying an expansion element carried by the turret, and gearing between said expansion element and said rack face including a camming member.

2. In a flexible gun mount for aircraft, a fixed base having an annular rack face, a revoluble gun-supporting turret mounted on said base, and wind pressure compensating means embodying an expansion element carried by the turret, gear wheels one of which

meshes with said rack face, and a thrust member acted upon by said expansion element and having a cam connection with one of said gear wheels.

5. 3. In a flexible gun mount for aircraft, a fixed base having an annular rack face, a revoluble gun-supporting turret mounted on said base, and wind pressure compensating means embodying an expansion element carried by the turret, and gearing between said expansion element and said rack face operating to increase the pressure of said expansion element proportionately to any increase of air pressure on the gun.
- 15 4. In a flexible gun mount for aircraft, a fixed base having an annular rack face, a revoluble gun-supporting turret mounted on said base, and wind pressure compensating means embodying an expansion element carried by the turret, and gearing between said

expansion element and said rack face operating when the turret turns under varying air pressures on the gun to proportionately vary the resisting force of said expansion element.

- 25 5. In a flexible gun mount for aircraft, a fixed base having an annular rack face, a revoluble gun-supporting turret mounted on said base, and wind pressure compensating means embodying an expansion element carried by the turret, gear wheels one of which meshes with said rack face, and a thrust member acted upon by said expansion element and having a cam connection with one of said gear wheels which causes a variation 30 in the resisting force of the expansion element proportionate to the varying air pressure of the air on the gun.

In testimony whereof I affix my signature.

HENRY B. INGLIS.
